DISPLAY

Lee L. Rakes, Chicago, Ill.

Application February 29, 1956, Serial No. 568,587

5 Claims. (Cl. 40—28.3)

This invention is concerned generally with a display item, particularly one for the Christmas season.

Christmas displays are widely used in the home, in stores, and in many other places. Such displays generally include a lighted Christmas tree, and may additionally include other items. Generally speaking, the displays are quiescent, or else any moving part continues to operate. Sometimes Christmas tree lights are arranged to flash on and off by means of a thermal timer incorporated in the lighting system, but this timer or flashing switch must be removed manually if it is desired for the lights to remain burning constantly. Most Christmas displays are substantially alike. Thus, none is readily distinguished or attracts any attention relative to any others. Christmas displays generally are left up for a period from several days to several weeks, and the unchanging appearance of each display, coupled with the sameness of substantially all displays, tends to lead one to tire of seeing Christmas displays.

Accordingly, it is an object of this invention to provide a display, particularly a Christmas display, which is different from other displays, and will attract the attention of the observer.

More specifically, it is an object of this invention to provide a Christmas display which is neither quiescent nor simply repetitive, but which changes markedly in character from time to time in accordance with a pre-arranged sequence.

More particularly, it is an object of this invention to provide a Christmas display including a tree mounted for movement, a village scene and train beneath the tree, and a phonograph or other sound reproducer, and control means, both automatic and manual, for operating the same in any predetermined sequence.

Other and further objects and advantages and the specific details of an illustrative embodiment of the invention will be apparent from the following description and the accompanying drawings forming a portion of the disclosure wherein:

Fig. 1 is a perspective view generally showing the illustrative parts of the invention;

Fig. 2 is a vertical cross section through the base or stand of the Christmas tree;

Fig. 3 is a horizontal section therethrough substantially along the line 3—3 of Fig. 2;

Fig. 4 is a somewhat diagrammatic top view of the phonograph;

Fig. 5 is an enlarged detail view partly in longitudinal section of the central support for the tree as taken along the line 5—5 in Fig. 3; and

Fig. 6 is an electrical wiring diagram for the invention. Referring now in greater particularity to the drawings, and first to Fig. 1, there will be seen a Christmas tree generally designated by the numeral 10 mounted on a base 12. The Christmas tree is provided with the usual ornaments, and with a plurality of lights 14. Beneath the tree there is arranged a village scene including a plurality of houses 16 having lights therein which will shine

2

out through the windows and doors of the houses. There is also provided a toy train track 18 encircling the tree and having a train 20 thereon. Off to one side there is provided a phonograph 22.

The base 12, as will be seen more particularly in Figs. 2 and 3, includes a cylindrical outer shell 24 having a surface covering 26 providing ornamentation thereon. The base 12 is provided with a base plate 28 resting on the floor or the like, and a cup 30 is positioned centrally of this base plate, the cup having a ball 32 rotatably resting thereon. A shaft 34 rests on the ball 32, and it will be understood that the cup and shaft, or one of them at least, has an indentation for properly positioning the ball 32. It will be apparent that the shaft could alternatively be supported by other means, such as ball bearings. The shaft is maintained in upright position by means of suitable spacers 36, which may take the form of solid plates or of webs, or any other desirable construction, and which preferably are provided with bearings of some sort through which the shaft 34 extends. At the upper end of the shaft 34 there is provided a cup 38 receiving the base of the tree 10, and having suitable clamping screws 40 or the like for mounting the tree. The cup is shown as integral with the shaft, but it can be detachable, as will be understood.

An electric motor 42 is mounted within the cylindrical housing 24 by means of suitable brackets 44, and the output shaft of the motor is provided with a relatively small pinion 46 meshing with and driving a larger gear 48 secured on the shaft 34 for driving this shaft at a reduced speed.

The shaft 34 is provided with a central bore 50 through which a pair of wires 52 leads to a pair of slip rings 54 or the equivalent mounted on the circumference of the shaft, and insulated therefrom. The wires at the upper end of the shaft pass radially outwardly through the cup 38 to a socket 56 into which the plug of the tree lights 14 is inserted. Brushes 58, or some other desirable type of sliding contact, are carried in insulated manner by suitable bracket means 60 (Figs. 2 and 3) in contacting engagement with the slip rings 54 or the like. Wires 62 connect the brushes or the like 58 with appropriate relays in a relay box 63 as will be set forth hereinafter with regard to the electrical circuit. The relay box preferably is located within the base, as shown, but can be located externally thereof.

The phonograph 22 mentioned earlier includes a cabinet 64 (Figs. 1 and 4) having a loudspeaker 66. The phonograph may be of standard design and includes the usual turntable 68, having a record thereon, preferably of Christmas music, and pickup arm 70. A switch 72 is affixed to the inside of the side wall of the cabinet and is provided with a bush-button actuator 74 thereon. It will be understood that the turntable 68 and arm 70 comprise parts of a conventional automatic record changer of any suitable type. When the arm 70 returns from the solid line playing position to the dash line position of Fig. 4 at the end of the record, the arm 70 engages the push-button 74 of the switch 72 to actuate a control function as will be brought out hereinafter.

The electrical construction of the step switch and relay box 63 will be seen with regard to Fig. 6, the box being indicated by broken lines. The box 63 is provided with a flexible service wire 76 having a plug 78 on the end thereof for insertion into a wall socket. Within the box 63 one side of the line or wire 76 is connected through a fuse 80 to a bus line 82.

Also within the box there is provided a stepping switch 84. This stepping switch is of well known design including a plurality of fixed contacts 86, there being ten such contacts in the present illustrative embodiment, and

also including a movable switch contact 88. The movable switch contact is connected to a bus line 90, and the other of the wires of the lead 76 is connected to this bus line. The first fixed contact 86 is not connected to anything. The remaining contacts, numbered 2 through 10, are connected through relay coils 92, conveniently numbered 1 through 9. The opposite side of each relay coil 92 is connected to the bus line 82.

The movable switch contact 88 is arranged to be moved step-wise by a stepping coil, as will be understood, each time the stepping coil is energized. The stepping coil is hereinafter identified by the numeral 94. One end of this stepping coil is connected to the bus 82. The other end is connected through three switches in parallel to the bus line 90. These switches comprise the phonograph switch 72 (in series with a toggle switch 95), a time switch 96 (in series with a toggle switch 97), and a push-button switch 98. The time switch 96 may be of any standard type, and conveniently is mounted within the box 63, but may be mounted outside thereof. The push-button switch 98 is shown also in Fig. 1, and is mounted outside of the box, a flexible connecting cable 100 leading from the push-button switch to the box. This push-button switch is of the well known type which is normally open, and which is closed upon depression of the push-button, the switch reopening under the influence of a spring upon release of the push-button.

There is also a plurality of groups of relay switches, such groups respectively being numbered 102, 104, 106, 107 and 108. One side of all of the relay contacts is connected to the bus line 90. The relay contacts are of the type which are normally open, and which are closed upon energization of a corresponding coil. Thus, the first group of switches, group 102, has switch contacts which are closed by any of the relay coils 8, 5, 1, 3, 4, 6 or 7. Switches 8 and 5 are connected together at a junction 110 and lead through a cam operated switch 112 to a junction 114. The remaining switches of group 102, namely switches 1, 3, 4, 6 and 7 are connected together to the junction 114, and the junction 114 is connected to the tree lights socket 56, the other side of the socket being connected to the bus line 82. The cam operated switch 112 may be supported in any suitable manner within the housing 24 and engages a cam 116 on the tree supporting shaft 34. Alternatively, this cam could be provided in a timer.

In the group of switches 104, switches 2 and 6 are connected together to a junction 118. Switches 7 and 8 are connected together to a cam switch 120, and the cam switch is connected to the junction. The junction 118 is connected to a socket 122 for the village lights within the houses 16. The cam switch 120 may be mounted for actuation by a cam 124 (Fig. 5) on the shaft 34, similarly to the switch 112. Of course, the switch 120 could be time operated.

All of the group of switches 106 are connected in common to a socket or connection 126 for the motor, and the group of switches 108 is connected to the socket 128 for the phonograph.

The time switch 96 is provided with a motor, as will be understood. One side of the motor is connected through the line to the bus line 90. The other side of the motor is connected through a wire 130 to the bus line 82. Thus, whenever the plug 78 is inserted in a wall socket the time switch will be running. It will be understood that a switch could be incorporated in the lead line or wire 76 if so desired. Assuming that the movable switch contact 88 is on fixed switch contact #1, and the time switch 96 is open when the plug 78 is inserted, nothing will happen relative to the display. After a predetermined time the time switch will close momentarily, thereby actuating the stepping coil 94, and moving the movable contact 88 to fixed contact #2. This will actuate relay #1 coil, and accordingly will close switch

contacts 1 of the group 102, thereby causing the tree lights to burn.

After a predetermined time lapse the time switch again will operate, and will act through the stepping coil 94 to move the movable contact 88 to fixed contact #3. This energizes coil #2, and hence closes switch contacts 2 of the group 104, thereby causing the village lights to be turned on. The tree lights simultaneously are turned off through de-energization of relay coil #1, and opening of switch contacts 1 of group 102.

After another predetermined time interval, the time switch will operate, and relay coil #3 will be energized. This causes switch contacts 3 to close in group 102 and also in group 106. This causes the tree lights to burn, and energizes the motor so that the tree is rotated. It will be understood that at the same time the relay coil 2 is de-energized, and the village lights are turned off.

Following another predetermined time interval, the time switch operates to move the movable contact to contact #5, thereby energizing relay coil #4, and closing all of the switch contacts #4, such switch contacts being in groups 102, 106, 107 and 108. As a result of this, the tree revolves, the tree lights are on, the train runs, and the phonograph plays. The time interval in this instance is not ended by the time switch. The interval of the time switch is longer than the time necessary to play a record on the phonograph. Accordingly, when the arm 70 of the phonograph returns to rest position and closes the phono switch 72 (assuming the toggle switch 95 to be closed as the switch 97 has been assumed to be closed), the phono switch causes energization of the stepping coil, and moves the movable contact 88 from fixed contacts #5 to fixed contact #6.

This is necessary in order to prevent the time switch from operating first, and thereby stopping the phonograph in the middle of a record. Aside from the undesirability of stopping in the middle of a record, it will be apparent that subsequent starting in the middle of a record would be most disconcerting due to the unpleasant noises that would be caused before the turntable came up to operating speed.

Contacting of the fixed switch 6 causes energization of the relay coil 5, and hence closing of the contacts 5 in group 102 and in group 106. This causes the tree lights to be lighted, and the motor to operate to rotate the tree. Rotation of the tree supporting shaft 34 causes the cam switch 112 to be opened and closed, thereby causing the tree lights to blink as the tree rotates.

Following another predetermined time interval the time switch again operates, and the movable contact moves from fixed contact #6 to fixed contact #7. In this instance the village lights are turned on along with the tree lights, and the tree is stationary.

The passing of another time interval causes the time switch to move the movable contact from contact 7 to contact 8. In this instance the tree lights are on, the motor runs to rotate the tree, and the village lights blink upon opening and closing of the cam switch 120 of group 104.

After another time interval has elapsed the movable contact shifts from fixed contact #8 to fixed contact #9. This causes all of the various parts of the display to operate at the same time. The tree lights and the village lights both blink on and off, the tree rotates, the train runs, and the phonograph plays. Upon completion of a record, the phono switch operates to terminate this portion of the sequence by moving the contact 88 to fixed contact #10. This causes energization of coil #9, and coil #9 is a reset coil which acts to reset the movable contact back to fixed contact #1.

An illustrative embodiment of the invention now has been fully disclosed. It will be apparent that other items could be added to the display, and operated in the proper sequence by the time switch 96 and the phonograph switch 72. In the illustrative embodiment, and in other embodi-

ments of the invention, it is of extreme importance to note that the push-button switch is in parallel with the phonograph switch and with the time switch. Thus, if for any reason it is desired to terminate one portion of the sequence prior to its normal time, all that is necessary is to depress the button of the push-button switch. This can be done several times to skip certain portions of the sequence if it should be so desired.

It will be understood that the toggle switch 95 can be left open to remove the cycle from the control of the phonograph, and records will play in succession. If the toggle switch 97 also is left open, any portion of the cycle will remain in operation until changed manually by the push-button switch 98. If the toggle switch 95 is closed, and the toggle switch 97 is opened, the cycle will be controlled manually and by the phonograph.

It will be apparent that the display heretofore disclosed has both a visual and an auditory appeal, and is calculated to attract the attention of anyone in the vicinity. The display can be used indoors, or it can be used outdoors with a weather-proof base. Alternatively, the display can be used outdoors with the control box indoors, and in this instance weather-proofing is not critical. Various changes in structure will no doubt occur to those skilled in the art, and are to be understood as forming a part of the invention insofar as they fall within the spirit and scope of the appended claims.

The invention is hereby claimed as follows:

1. A Christmas display comprising a plurality of items including a Christmas tree mounted on a rotatable stand, lights on said Christmas tree, and a scene adjacent said Christmas tree and having lights thereon, said items being alternatively quiescent or activated to appeal to at least one of the perceptive senses, a plurality of switch means operable individually and in groups for similarly rendering said items quiescent or activated, time switch means for operating said plurality of switch means individually and in groups in predetermined order, and manually operable switch means connected in parallel with said time switch means for operating said plurality of switch means irrespective of the operation of said time switch means.

2. A display as set forth in claim 1 wherein the plurality of switch means comprises a stepping switch, a plurality of relays selectively energized through said step-

ping switch, and a plurality of relay switches, said items being connected singly and in groups to said relay switches, and further including a relay coil energized through said time switch means or said manually operable switch means for operating said stepping switch.

3. A display comprising a Christmas tree, a stand mounting said Christmas tree for rotation, lights on said Christmas tree, a setting beneath said Christmas tree having a plurality of lights and a toy train, controlling means for alternately starting and stopping said train and turning on and off said setting lights in accordance with a predetermined pattern, said controlling means selectively effecting rotation and stopping of said Christmas tree, and switch means opened and closed by rotation of said Christmas tree for turning said lights off and on.

4. A display as set forth in claim 3 and further including a phonograph, the controlling means effecting starting of said phonograph, and said phonograph further having a switch operable upon the completion of a record playing operation to shut off said phonograph and to act instead of said controlling means to change the condition of the remaining parts of the display.

5. A display comprising a plurality of items alternatively quiescent or activated to appeal to at least one of the perceptive senses, one of said items having an independent time cycle, a plurality of switch means connected to said items for changing the condition of quiescence or activation thereof, means for operating said plurality of switch means in accordance with a predetermined pattern and means operated by the item having the independent cycle for operating said switch means independently of the pattern operating means.
